We claim the ornamental design for an audio electronic device, as shown and described.

DESCRIPTION

FIG. 1 is a top perspective view of one embodiment of an audio electronic device comprising a new, original and ornamental design;

FIG. 2 is a bottom perspective view of the audio electronic device shown in FIG. 1;

FIG. 3 is a front elevation view of the audio electronic device shown in FIG. 1;

FIG. 4 is a rear elevation view of the audio electronic device shown in FIG. 1;

FIG. 5 is a right side view of the audio electronic device shown in FIG. 1;

FIG. 6 is a left side view of the audio electronic device shown in FIG. 1;

FIG. 7 is a top plan view of the audio electronic device shown in FIG. 1;

FIG. 8 is a bottom plan view of the audio electronic device shown in FIG. 1;

FIG. 9 is a top perspective view of a second embodiment of the audio electronic device shown in FIG. 1;

FIG. 10 is a bottom perspective view of the audio electronic device shown in FIG. 9;

FIG. 11 is a front elevation view of the audio electronic device shown in FIG. 9;

FIG. 12 is a rear elevation view of the audio electronic device shown in FIG. 9;

(Continued)

FIG. 13 is a right side view of the audio electronic device shown in FIG. 9;
 FIG. 14 is a left side view of the audio electronic device shown in FIG. 9;
 FIG. 15 is a top plan view of the audio electronic device shown in FIG. 9;
 FIG. 16 is a bottom plan view of the audio electronic device shown in FIG. 9;
 FIG. 17 is a top perspective view of a third embodiment of the audio electronic device shown in FIG. 1;
 FIG. 18 is a bottom perspective view of the audio electronic device shown in FIG. 17;
 FIG. 19 is a front elevation view of the audio electronic device shown in FIG. 17;
 FIG. 20 is a rear elevation view of the audio electronic device shown in FIG. 17;
 FIG. 21 is a right side view of the audio electronic device shown in FIG. 17;
 FIG. 22 is a left side view of the audio electronic device shown in FIG. 17;
 FIG. 23 is a top plan view of the audio electronic device shown in FIG. 17; and,
 FIG. 24 is a bottom plan view of the audio electronic device shown in FIG. 17.
